UNITED STATES PATENT OFFICE.

EDWARD H. BUTTERFIELD AND FERDINAND D. OTTERBEIN, OF MIDDLETOWN, OHIO,
ASSIGNORS TO TOM HARVEY, JR., OF MIDDLETOWN, OHIO.

PROCESS OF PAPER MANUFACTURING.

Application filed May 12, 1919. Serial No. 296,688.

To all whom it may concern:

Be it known that we, EDWARD H. BUTTERFIELD and FERDINAND D. OTTERBEIN, citizens of the United States, residing at Middletown, in the county of Butler and State of Ohio, have invented certain new and useful Improvements in Processes of Paper Manufacturing, of which the following is a specification, reference being had therein to the

10 accompanying drawing.

This invention relates to an improved process of paper manufacturing and has for its particular object to provide a new process for automatically regulating the 15 weight or thickness of the paper web and controlling the same from the formation of the web at the wet end of the machine and indicating and recording the variations therein as it passes over the drying and finishing rollers of the machine.

Heretofore the practice has been to require the machine attendant or foreman in charge to make frequent tests of the paper by puncturing the web and measuring the 25 thickness thereof as it travels over the forming and finishing rollers to determine whether the web was running to required dimensions. This method, for obvious reasons, is far from satisfactory. The measurements 30 are not made with any assured regularity or accuracy and are generally not acceptable to operators or customers as conclusive proof of the uniformity of the paper stock. Besides the practice of puncturing the paper web is 35 generally more or less objectionable as it leads to inconvenience and waste in the use that is subsequently made of the paper.

The former method of measuring the paper is further unsatisfactory in that the 40 paper is not always of uniform thickness throughout its width. The web may run heavy on one edge and light on the other and such conditions are not readily discovered by the method of examination referred 45 to.

Thus, it will be apparent that under the old methods of operation uniformity of weight of the paper sheet was entirely dependent, first, upon a human element as to the 50 frequency and accuracy in which measurements would be made, and, secondly, upon a crude and at best haphazard method of taking measurements. This failure of having means for positively and accurately con-

trolling the weight of the paper as it is developed on the forming machine and therefore no authoritative record of the limits in thickness maintained in any given lot of paper has been the cause of endless contentions between manufacturers and consumers 60 involving claims and counter claims for adjustments.

It is the purpose of the present invention, therefore, to overcome these difficulties by the use of an improved process of paper 65 manufacturing, whereby the weight of the paper as it is formed and delivered over the machine will be automatically regulated and the thickness of the web maintained within the limits allowed by the specifications without intervention of any human element. It is a further object of our invention to cause 70 a record, in the form of a graphic chart, to be made in connection with the improved process of control which will be indisputable 75 evidence as to the thickness of the paper throughout the length and breadth of the sheet.

The mechanical devices in one form, by means of which our improved process may 80 be applied, form the subject matter for a companion application for Letters Patent filed May 12, 1919, Serial No. 296,687, and are here shown in the accompanying drawings for illustration purposes. It will be 85 understood that the present invention is not limited in the application thereof to any specific form of mechanism, but may be applied in combination with any mechanical devices suitable to the purposes of the in- 90 vention.

Referring to the accompanying drawings: Fig. 1 is a detailed side elevation of a part of a paper-forming machine having an improved metering instrument of the type disclosed in our copending application referred 95 to applied thereto and illustrating the application in one form of a feature of our improved process;

Fig. 2 is a front elevation of the arrangement shown in Fig. 1;

Fig. 3 is a front elevation of a metering instrument of the type shown in Figs. 1 and 2 and a further illustration of its application in connection with our improved 105 process.

Fig. 4 is an illustrative outline view of suitable mechanism in one form, whereby in

connection with the process the metering instrument may be employed to automatically regulate the thickness of the paper as it passes over the machine by automatically regulating the supply of raw material thereto;

Fig. 5 is an illustrative outline view of suitable mechanism in another form, whereby the metering instrument used in connection with the process may be employed to regulate the thickness of the paper by automatically regulating the speed of the paper forming machine;

Fig. 6 is a front elevation of the metering instrument as applied in the process having connections whereby the instrument will be automatically regulated to move transversely across the face of the paper;

Figs. 7 and 8 are illustrative diagrammatic views of an arrangement of electrical wiring whereby the purposes of the invention may be realized with any suitable form of apparatus;

Figs. 9 and 10 are vertical cross sectional views respectively of different portions of the metering instrument;

Fig. 11 is a detail view in cross section of the pulp supply tank; and

Fig. 12 is an illustrative graphic chart in one form such as may be used to make a record of the variations in the thickness of the paper produced under our process.

In its preferred form the improved process may be applied and the purposes of the invention realized on the ordinary type of paper forming machine. As here shown the process consists in delivering the raw paper stock from a supply box 1, best shown in Figs. 4 and 11 of the drawings, to the forming roller 7^a at the wet end of the machine. The supply box for the raw material may be of any suitable construction, the particular construction shown being for the purposes of illustration only. As here shown the box is divided into compartments 3, 4 and 5, the raw material being delivered to compartment 3 from any suitable source, such as a stuff chest, not shown, which is common to all well known processes of paper manufacturing.

From the compartment 3 the amount of material required for the machine is discharged through a gate or slide valve 6 into the space 4 of the box; the surplus overflowing into compartment 5 is returned to the stuff chest through a pipe 7. The material required for the machine is delivered through a pipe 6^a to a tank 6^b and from the tank is supplied to cylinder molds 7^a and through the usual successive steps of web formation at the wet end of the machine to the first series of drying cylinders 8 where an important step of the new process takes place.

At this point the newly formed paper

sheet is caused to come in contact with a measuring device 9 of a metering instrument which consists essentially of indicators 10 and 11, (seen more clearly in Figure 2) each having a dial 12 and hands or pointers 13 in synchronized operation with the measuring device 9. The indicator 10 is further provided with a pointer 14 which serves to indicate on the dial 12 the mean dimension in thickness for the paper being formed on the machine. The dials, as here shown, show graduations of one-thousandths of an inch. The pointers 13, therefore, being controlled by and having synchronous movement with the measuring devices 9, serve to indicate on the dials the variations in thickness of the paper web.

As shown in Fig. 3 of the drawings, a differential signalling device may also be employed in the process in connection with the metering instrument. As here shown the signals consist of electric lights in different colors and arranged in a group. The light 15 is preferably a white light and serves to indicate when the light is on that the paper web is running normal, i. e., at the mean dimension in thickness under the measuring dev. 9; the light 16 is preferably a red light and serves to indicate when the red signal is on that the paper is running heavier than normal but within the allowed plus limits of variations; the light 17 is preferably a blue light and serves to indicate when in operation that the paper is running lighter than normal but within the allowed minus limits of variations.

Contact points 18, 19 and 20 (see Figures 1, 4, 7 and 8) may be disposed in any suitable manner between the pointer 13 and the signal lights, whereby the variable movements of the pointer will act to cause operation of the lights accordingly as the paper may vary in thickness. In event that the paper runs outside the allowed limits in thickness either plus or minus all of the lights will be out. Thus the attendant of the machine may be constantly informed by observation of the signal lights how the paper is running as to weight or thickness.

A further important step in the process is provided for in connection with the metering instrument. As above stated, it is of great importance to produce in connection with the process of manufacturing an indisputable record showing the variations in thickness of the paper sheet throughout the length and breadth thereof.

To this end there is combined with the metering instrument means controlled essentially by the measuring device 9, whereby a record, preferably in the form of a graphic chart, will be delineated by the variation movements thereof. As here shown (see Fig. 10) such an instrument may consist in one form of a cylindrical

casing 21 having rotatably supported therein a cylindrical support 22 for a graphic chart of the character described and shown in Fig. 12, and as illustrated in Fig. 10, the cylinder and chart being supported within the casing in any suitable manner and preferably actuated by a suitable clock movement within the cylinder. The recording instrument may consist of a suspended carriage 23 and contact member 23^a supported upon guides 24 and operable longitudinally of the chart in the upward direction by a cable 25 connected in any suitable manner to the measuring device 9.

As shown in Fig. 12 the chart is divided longitudinally, its greater length extending circumferentially around the cylinder, by light lines which represent variations of one-thousandth of an inch in the movement of the measuring device 9 and therefore in the thickness of the paper passing thereunder. The heavy longitudinal lines represent variations of five-thousandths and are provided for convenient reading of the chart. The heavy transverse lines represent hours of time and the light transverse lines fractions of hours; these divisions of time being made to agree with the clock movement by means of which the chart is rotatably actuated.

Thus it will be seen that a graphic chart of the character here shown may be produced in connection with our improved process which will show the exact variations in the thickness of the paper for the entire quantity run on any job or lot from which the record is made, and also that the record will show during what hours variations in the thickness were developed; this latter information being of primary importance in maintaining standards of efficiency in the work of attendants.

A further step in the process consists in causing the measurements of the metering instrument to be applied to substantially the entire length and breadth of the paper. One form of practical means for accomplishing this is illustrated in Fig. 3 of the drawings wherein the metering device is shown supported in guides or frames 26 and 27 secured to the main frames of the machine, and operable transversely of the paper by means of a screw shaft 28 which may be connected to the instrument in any suitable manner.

One of the main purposes of the improved process is to make the control of the means for regulating the weight of the paper as it is formed on the machine entirely automatic so that the human element and the methods of measuring heretofore employed relative to this important detail of production will be entirely eliminated. To this end any suitable form of controlling mechanism may be employed in connection with the

gate or slide valve 6 leading to the supply tank 4 (see Fig. 4) and controlled through the electrical contacts 19 and 20 by the movements of the measuring device 9. As best shown in Figs. 4 and 11 of the drawings, such an arrangement in one practical form may consist of an interpolar motor 29 in circuit with the contacts 19 and 20 and any suitable source of electrical current, and operably connected to the valve by a suitable construction, such as here shown, consisting of the gears 30 and 31, shaft 32 and screw shaft 33 connected to the gate member 34 of the valve.

In Figure 7 is shown the indicating mechanism previously described. To one lead of the main line is connected one terminal of the lamps 15, 16, 17. To the other lead of the main line is connected a pointer of the indicating mechanism. The lamps are each connected in series with the contact points 18, 19 and 20 upon which a portion of the pointer mechanism is adapted to bear. 18, 19 and 20 are shown diagrammatically insulated from each other. When the pointer is in the position indicated in Figure 7, the circuit is completed through one lead by the lamp 15, contact point 18 through the pointer and back to the main lead circuit. Should the pointer be in position for paper slightly under or over thickness then the circuit is completed either through lamp 16, contact point 19 and the pointer, or through lamp 17, contact point 20 and the pointer. Should the paper be over or under the desired maximum or minimum thickness, the pointer will not be in contact with any of the contact points 18, 19, 20 and none of the lamps will be lighted.

Thus when the paper web is running normal under the measuring device the pointer 13 (see Figs. 1 and 7) will register with the contact 18 which is not in circuit with the motor; the motor therefore will be at rest and the valve normally open. When the paper is running heavier than normal the pointer will register with the contact 19 and the motor circuit will be closed and the motor will operate to partially close the valve, thereby reducing the supply of material delivered to the machine and, the machine running at normal speed, the thickness of the paper will be accordingly reduced. When the paper runs lighter than normal the circuit will be closed through the contact 20 and the motor will be operated to open the valve to a greater extent, thus acting to increase the supply of material to the press and resulting in a corresponding increase in the thickness of the paper.

A further means of automatic control in connection with which the present invention may be applied consists in any suitable means for regulating the speed of an en-

gine or other power device whereby the paper forming machinery is operated. As shown in Fig. 5 such an arrangement may consist in one form of differential gearing 5 of any suitable construction interposed between the engine or motive power and the machine and controlled by a motor in the same manner as described. In the practical application of such an arrangement the 10 motor stands at rest when the paper is running normal and is actuated to regulate the governor of the engine by which the paper forming machine is operated to increase the speed of the engine when the paper runs 15 above normal, and to decrease the speed when the paper runs below normal; it being understood that the supply of raw material to the machine remains constant at normal and, therefore, that the required 20 regulation is effected entirely by the variable speed of the machine.

A further feature of our improved process consists in causing the newly formed paper web to come in contact with two of 25 the metering instruments, Fig. 5, one located relative to one of the drying rollers immediately adjacent the wet end of the machine and the other relative to one of the finishing rollers at the dry end of the machine. Under 30 certain conditions it may also be of advantage to use one or more of the instruments intermediate these points.

The instrument at the wet end of the machine under the process will serve to determine 35 the thickness of the paper and also control the limits of variation allowed in the specification by one or the other of the two arrangements described for automatic control of this essential dimension of the 40 paper,—i. e., by regulating the speed of the machine or the supply of raw material thereto. The process at this point preferably includes the use of the signals and the making of a graphic record in the manner and of the character described.

The process at the dry end of the machine 45 consists in applying an instrument to the paper substantially in the same manner as at the wet end of the machine, except that the automatic means of control are not required.

Thus by employing two or more instruments in connection a definite relation in the process may be maintained between the 50 different steps of forming, drying and finishing the paper and the records obtained will be indisputable evidence as to the uniformity or lack of uniformity of the paper produced.

As far as we are aware we are the first 55 to evolve and make practical application of a process of the character described, and we wish to claim the elements of the invention broadly therefore as defined and comprehended in the accompanying claims.

Having thus fully described our invention, what we claim as new and desire to secure by Letters Patent, is:—

1. The herein described process of paper manufacturing consisting in delivering the 70 raw material to the wet end of the machine in substantially the quantity required to form a paper web of predetermined thickness, in causing the web so formed to come in contact with a metering instrument to 75 actuate the same to produce indications to make a record of the mean thickness of the paper showing the plus and minus variations therefrom and to cause automatic regulation 80 of its thickness.

2. The herein described process of paper manufacturing consisting in delivering the raw material to the wet end of the machine in substantially the quantity required to form a paper web of predetermined thickness, in causing the web so formed to come in contact with a metering instrument to 85 actuate the same to produce a graphic record of the mean thickness of the paper and showing the plus and minus variations 90 therefrom during the interval of time in which the paper was made.

3. The herein described process of paper manufacturing consisting in delivering the raw material to the wet end of the machine 95 in substantially the quantity required to form a paper web of predetermined thickness, in causing the web so formed to come in contact with a metering instrument to actuate the same to produce a graphic record 100 of the thickness of the paper throughout the length and breadth thereof, and a signal agreeing therewith.

4. The herein described process of paper manufacturing consisting in delivering the raw material to the wet end of the machine in substantially the quantity required to form a paper web of predetermined thickness, in causing the web so formed to come in contact with a metering instrument to 105 actuate the same to cause operation of a plurality of differential signals to indicate the mean thickness of the paper and the plus and minus variations therefrom upon the 110 same machine.

5. The herein described process of paper manufacturing consisting in delivering the raw material to the wet end of the machine in substantially the quantity required to form a paper web of predetermined thickness, in causing the web so formed to come in contact with a metering instrument to 120 actuate the same to cause operation of a plurality of signal lights in different colors to indicate the mean thickness of the paper 125 and the plus and minus variations therefrom.

6. The herein described process of paper manufacturing consisting in delivering the raw material to the wet end of the machine 130

- in substantially the quantity required to form a paper web of predetermined thickness, in causing the web so formed to come in contact with a metering instrument to 5 actuate the same to cause operation of a plurality of differential colored signals to indicate the plus and minus variations from the mean thickness of the paper.
7. The herein described process of paper 10 manufacturing consisting in delivering the raw material to the wet end of the machine in substantially the quantity required to form a paper web of predetermined thickness, in causing the web so formed to come 15 in contact with a metering instrument to actuate the same to cause automatic regulation of the thickness of the paper and to produce an indication and a signal relative thereto and to make a graphic record there- 20 of.
8. The herein described process of paper manufacturing consisting in delivering the raw material to the wet end of the machine in substantially the quantity required to
- form a paper web of predetermined thick- 25 ness, in causing the web so formed to come in contact with a plurality of metering instruments to actuate the same, whereby graphic records will be produced showing the relative thickness of the paper web at 30 the wet and dry ends of the machine.
9. The herein described process of paper manufacturing consisting in delivering the raw material to the wet end of the machine in substantially the quantity required to 35 form a paper web of predetermined thickness, in causing the web so formed to come in contact with a plurality of metering instruments to actuate the same, whereby a plurality of signal lights in different colors 40 will indicate the relative thickness of the paper web at the wet and dry ends of the machine.

In testimony whereof, we affix our signatures.

EDWARD H. BUTTERFIELD.
FERNAND D. OTTERBEIN
